WARP BEAM

Stephen Miller Fulton and William Beggs
McVeigh, Spondon, near Derby, England, as-
signors to Celanese Corporation of America, a
corporation of Delaware

Application February 10, 1931, Serial No. 514,766
In Great Britain April 1, 1930

2 Claims. (Cl. 242—124)

The present invention relates to warp beams, and more particularly to warp beams whose flanges are adjustable along the beam to give any required distance between the flanges.

5 In the usual type of flanged warp beam, the flanges are clamped on to a wooden or metal barrel and have a tendency to slip under the pressure of the yarn during processing. If, in order to overcome this difficulty, screwed flanges threaded on to the beam are employed, defects may arise as the result of mutilation of the threads on the beam. Thus, if the flanges are secured in ad-
10 justed position by means of set-screws which engage longitudinal slots in the threaded portions of the beam, the threads on the beam may be damaged should the set-screws not be withdrawn sufficiently from the slots when it is required to screw the flanges along the beam for adjustment, or should the set-screws be tightened while they
15 are not registering with the slots.
20 The object of this invention is to provide a warp beam having a screwed barrel and flanges which can be firmly secured thereon in any adjusted position, in which any risk of damaging the screw
25 is obviated.

25 A warp beam according to the invention comprises a barrel, a flange adapted to be screwed on to external threads at an end of the barrel, and means for locking together the threads of the flange and the barrel. Thus, for example, 30 a metal flange may have a relatively thin boss extending towards the end of the barrel, which boss is slotted so that it can be compressed into firm engagement with the barrel by means such as a split collar surrounding the boss and capable of being tightened round the boss, or a taper threaded nut for engagement with tapered screw portions on the outside of the boss. Another 35 method of locking the flange in position consists in screwing a lock nut on the barrel and into engagement with the flange to compress together the threads of the flange and the barrel. The flanges at each end of the beam may be adjustable in the manner above set forth in order that they may be symmetrically arranged along the
40 length of the beam.
45 The beam barrel may consist of a metal tube whose ends are screwed to secure the flanges, or a wooden or other non-metallic barrel may be used, to whose ends threaded metal tubes are secured to receive the screwed flanges.

50 Forms of beam according to the invention will now be described by way of example with respect to the accompanying drawing, in which:—
55 Fig. 1 is an elevation and sectional elevation

of the left and right hand ends respectively of a warp beam, fitted with one form of flange-locking device,

Fig. 2 is a sectional end elevation on the line 2—2 of Fig. 1,

Fig. 3 is a part-sectional elevation of another form of flange-locking device fitted to the end of a warp beam,

Fig. 4 is a part-sectional end elevation on the line 4—4 of Fig. 3, and

Fig. 5 is an elevation of a further form of flange-locking device.

In Fig. 1, a beam barrel 6 of iron, steel, aluminum or other metal is provided with a finely threaded portion 7 extending for some distance from its ends. Threaded on to this portion 7 is a flange 8 provided with an internally threaded boss 9 having a reduced portion 10 of relatively small thickness. A number of slots 11, four of which are shown, are provided in this reduced portion 10 for some distance from the end and pass completely through the thickness of the boss in order to provide flexibility and allow the internal threads of the boss to be compressed into engagement with the threads of the beam barrel. 70

110

Mounted on the reduced portion 10 is a locking collar 12 provided with lugs, a clearance slot 13 between the lugs, and a bolt 14 passing through the lugs, by means of which the collar may be contracted and caused to nip on the reduced portion of the boss to cause the threads of the flange and beam barrel to be locked together. A slight recess (not shown) may be provided in the outer surface of the reduced portion 10 to receive the locking collar 12, so that there is no tendency for the collar to slip off the boss when the bolt 14 is slackened off.

The threaded end portion of the beam 7 is provided with an end cap 15 having a journal pin 16 for carrying the warp beam either in a warp beaming machine or in a loom, and holes 17 are provided at intervals along the barrel 6 in order that the warp which is to be wound on to the beam may be secured therein.

In Figs. 3 and 4, the flange 8 has a boss 9, slots 11 passing completely through the boss for some distance from its end, which boss 9 is provided with a tapered external thread 18 on which is mounted a nut 19 having a tapered internal thread and slots 20 on its periphery for engagement with a tightening tool, so that rotation of the nut up the tapered thread causes the boss to be contracted and thereby lock together the threads of the flange and beam barrel.

In Fig. 5, a beam barrel 6 is provided with a 110

threaded portion 7, and a flange 8 having an internally threaded boss 9 adapted to be screwed on to the threaded beam barrel 7. A lock-nut 21 provided on the threaded portion 7 is tightened 5 against the end face of the boss to secure the flange in position.

When it is required to adjust the width between the flanges, the locking collars or nuts, as the case may be, are slackened, the flanges 10 screwed along the beam to the required positions, and the locking collars or nuts are tightened again. With this arrangement the flanges remain perfectly square with the beam barrel in any adjusted position, and no risk of damage to the 15 thread is occasioned during the movement of the flanges or in securing them in position.

It will be seen that once the flanges have been secured upon the beam barrel by the tightening up of the locking device, it is impossible for the 20 flanges to slip under pressure of the yarn during processing.

What we claim and desire to secure by Letters Patent is:—

1. A warp beam comprising a barrel with an externally threaded end, an internally threaded flange adapted to be screwed and adjustably positioned on said end, said flange being provided with a slotted and internally threaded boss adapted to be screwed on said end and a collar surrounding the internally threaded, slotted boss to contract said slotted boss so as to press the threads of the flange on to those of the barrel. 80

2. A warp beam comprising a barrel with an externally threaded end, an internally threaded flange adapted to be screwed and adjustably positioned on said end, said flange being provided with a slotted and internally threaded boss, said boss being provided with a tapered external thread and an internally threaded collar adapted to screw on and contract said slotted boss so as to press the threads of the flange on to those of the barrel. 85
